IMPELLER HAMMER FOR SILO UNLOADER
OR THE LIKE

Floyd E. Buschbom, R.R. 3, Albert Lea, Minn.

Filed June 20, 1957, Ser. No. 46,661

Term of patent 14 years

(Cl. D55—1)

FIG. 1

FIG. 2

FIG. 3

FIG. 4

FIG. 5

FIGURE 1 is a top plan view of an impeller hammer for silo unloader or the like, showing my new design;

FIGURE 2 is a side elevational view thereof;

FIGURE 3 is a left end elevational view taken with reference to FIGURE 2;

FIGURE 4 is a right end elevational view taken with reference to FIGURE 2; and

FIGURE 5 is a top perspective view thereof taken from the right of FIGURE 2.

I claim:

The ornamental design for an impeller hammer for silo unloader or the like, as shown.
